CLAIM

The ornamental design for a UV ceiling light, as shown and described.

DESCRIPTION

FIG. 1 is a front view of a first embodiment of a UV ceiling light, showing our design;

FIG. 2 is a rear view thereof;

FIG. 3 is a left side view thereof;

FIG. 4 is a right side view thereof;

FIG. 5 is a bottom view thereof;

FIG. 6 is a top view thereof;

FIG. 7 is a perspective view thereof;

FIG. 8 is enlarged view of the indicated portion in FIG. 7;

FIG. 9 is a top perspective view thereof;

FIG. 10 is a bottom perspective view thereof

FIG. 11 is a front view of a second embodiment of a UV ceiling light;

FIG. 12 is a rear view thereof;

FIG. 13 is a left side view thereof;

FIG. 14 is a right side view thereof;

FIG. 15 is a bottom view thereof;

FIG. 16 is a top view thereof;

FIG. 17 is a perspective view thereof;

FIG. 18 is enlarged view of the indicated portion in FIG. 17;

FIG. 19 is a top perspective view thereof; and,

FIG. 20 is a bottom perspective view thereof.

The broken line showing in the Figures shows portions of the UV ceiling light and forms no part of the claimed design.

The broken lines of alternating length in FIGS. 7, 8, 17, and 18 are for the purpose of illustrating the boundaries of the enlarged fragments and also form no part of the claimed design.
